PLURAL-PART BEARING FOR SPINNING-
AND TWISTING SPINDLESWalter Hoffmann, Zurich, Switzerland, assignor
to Actiengesellschaft Joh. Jacob Rieter & Cie.,
Winterthur, SwitzerlandApplication April 12, 1949, Serial No. 87,097
In Switzerland January 14, 1949

6 Claims. (Cl. 308—152)

1

It is known in the spinning art to accommodate the bolster and step of plural-part bearings for spinning and twisting spindles in sleeve, and to suspend the bolster and step oscillatably in the spindle housing, abutting against a spherical face of the latter. It has been found, however, that such a bearing arrangement does not sufficiently take into account the forms of oscillation of the spindle blade which are set up by an unbalanced yarn package which forms of oscillation depend on the speed of rotation. The spindle blade seizes at the bolster, as is known from experience, so that the latter is easily damaged, especially when handling large and heavy yarn packages. Moreover, the manufacture of oscillatable bearing sleeves of the type mentioned is costly on account of the requisite long bores. Furthermore, relatively complicated, partly additional, means are necessary for clamping the oscillatable sleeve to the spindle housing.

It also has been proposed, in a different type of spindle, to interconnect elastically the bolster and step, for example, by means of a helical spring. The bolster in such spindles is capable of adapting itself to the movement of the spindle blade independently of the step, but such movement disadvantageously is not guided, and the spindles, therefore, are subjected to excessive vibration, in particular when passing through critical speed ranges. Since the bolster is carried only by one or a few turns of the helical spring, the radial resilience in the various directions is unequal.

For the purpose of avoiding the said deficiencies and disadvantages, the bearing arrangement according to my present invention comprises a spherically mounted bolster head which is spring-pressed against the spindle housing and is connected to the step through a sleeve in a freely movable relation.

The bolster-head suitably is provided with a neck comprising a ruff and a recess in the latter. A helical spring is disposed on the said neck between said ruff and head, having an inside diameter which is smaller than the width of said ruff and an outside diameter which is larger than the said width. Advantageously a sleeve is used for interconnecting the bolster head and step, abutting against the upper end of the helical spring through its radially re-entering head end which has a recess, and carries the step in its foot portion.

An example of my present invention is shown in the accompanying drawing, in which—

Fig. 1 is a perspective view of the sleeve connecting the bolster-head and the step.

2

Figs. 2 and 3 show the bolster-head, and the step, respectively, also in perspective views,

Fig. 4 shows an axial section through the assembled bearing structure,

Fig. 5 shows a modification of the means connecting the sleeve and step, and

Figs. 6 and 7 are comparative schematic representations for explaining the mode of operation of a spindle having a conventional bearing arrangement and of a spindle having a bearing constructed according to my present invention.

The bearing proper for the spindle, disposed centrally therein, comprises the bolster head 1, the connecting sleeve 2, and the step bearing 3. An antifriction bearing (not shown) is disposed in the bolster head 1 which is provided with a spherical bearing face and a neck 4. The latter terminates in a ruff 5 which is recessed at 6. A helical spring 7, having an inside diameter smaller than the outside diameter of the ruff, is screwed onto the neck 4 through the recess 6. The bolster head 1 possesses an annular shoulder 8 (Fig. 4) which serves as an abutment for the sleeve 2 and for the said spring 7.

The connecting sleeve 2 consists of a thin-walled tube of a certain resilience, which at its upper end is furnished with an inwardly projecting flange 13 which is recessed at 14. A hole 15 is disposed in the wall of sleeve 2 below the border 13, and two inwardly projecting and diametrically opposite indentations 16 are provided in the foot portion of sleeve 2.

The step bearing 3, as shown in Fig. 3, comprises a set-back portion 9 having two diametrically opposite holes 10 for engagement by the indentations 16 provided on sleeve 2.

The modified means for connecting sleeve 2 and step 3, as shown in Fig. 5, comprise a sleeve 2' furnished with an inwardly projecting border 12, and a step bearing 3' provided with a set-back portion annularly grooved at 11 for the purpose of engaging the said border 12.

The clear inner width of the upper flange 13 of connecting sleeve 2 is somewhat greater than the diameter of ruff 5 on neck 4 of bolster 1, so that the sleeve 2, for the purpose of interconnecting the bearing portions 1 and 3, may be readily slid over the said ruff 5 until the flange 13 abuts with its downwardly facing surface against the spring 7 which previously has been screwed under preliminary stress onto the neck 4 of bolster head 1 through recess 6. The sleeve 2 then is turned until the end of spring 7 is engaged in the recess 14 of flange 13, whereupon the sleeve 2 is screwed upward on spring 7 until finally the flange 13 arrives above the upper end

of spring 7, that is, in a position intermediate of the latter and the annular shoulder 8 of bolster 1. In such position, the connecting sleeve 2 is pressed against the shoulder 8 of bolster head 1 through the spring 7.

In order to anchor the plural bearing structure in the housing 17, the sleeve 2 is so adjusted that its hole 15 is aligned with the tensioning screw 18 which then is tightened. The conical tip of screw 18 engages the lower edge of the hole 15, thus depressing the sleeve 2. The flange 13 of the latter thus is removed from the shoulder 8 of bolster head 1, and the pre-stressed spring 7 pulls the partially spherical face of bolster head 1 against the corresponding semi-spherical seat in the head of housing 17. When the sleeve 2 occupies such latter position, its indentations 16 no longer carry the step 3 which now rests on the bottom of housing 17 entirely independent of the connecting-sleeve 2 and only 15 loosely guided on its circumference by the wall of the housing 17.

It will be appreciated from the above description that the assembly of the three bearing parts 1, 2 and 3 is very simple.

The resilient flexibility of the connecting sleeve 2 is of importance in that the sleeve cross-section must be capable of being temporarily deformed in order to engage the indentations 16 of sleeve 2 in the holes 10 of step 3 and, thereafter, spring back into its initial shape. The modified connecting means shown in Fig. 5 operate on the same principle of deformation. The connecting sleeve suitably is made of a thin-walled sheet iron tube, although other materials such as plastics also may be used.

Fig. 6 refers diagrammatically to a spindle of conventional design, in which the bolster 20 and step 19 are rigidly interconnected in and through a common sleeve. The spindle blade 21 when quiescent assumes the position shown by dotted lines. When the yarn package is eccentrically loaded, which practically always is the case, the spindle blade is deformed in operation, for example, under the influence of an eccentric weight 22. The result is that the spindle blade 21 is subjected to binding in bolster 20, and thus both bearing portions are disadvantageously affected. Such binding, further, disturbs the inherent form of oscillation of the spindle blade, and the spindle no longer runs smoothly.

Fig. 7 relates to a spindle bearing arrangement according to the present invention, in which the spherically formed bolster 23 is entirely independent of the step 24, that is, loosely connected to the latter only to such extent that the step also is withdrawn when withdrawing the bolster 23 from the spindle housing. Such arrangement affords radial guide means for the bolster 23, while maintaining the adjustability in view of the various forms of oscillation of spindle blade 25 at different rotary speeds. A point of special importance is the independence of bolster 23 from the movements of step 24, causing a faultless, smooth operation of the spindle.

All the parts comprised in the bearing arrangement according to the present invention are distinguished by structural simplicity which renders the same particularly suitable for low-cost mass production.

What I claim as new and desire to secure by Letters Patent is:

1. In a spindle, a blade, a spindle housing, a bolster seat toward one end of the housing, a

bolster having a neck extending downwardly into said housing, said neck having a ruff spaced from the bolster proper, a sleeve fixed in said housing against longitudinal displacement, and overlapping the lower portion of the bolster neck, said sleeve having an inwardly extending flange at its upper end spaced from the ruff, a coil spring mounted on the neck above the ruff, said neck having a recess formed therein and in the ruff through which recess the spring is screwed to be mounted on the neck, the flange of the sleeve also having a recess through which the spring mounted on the neck is screwed in order to assemble the bolster and sleeve with the spring mounted between the flange of the sleeve and ruff of the bolster neck.

2. In a spindle, a blade, a blade mounting housing having a substantially semi-spherical bolster seat, a bolster mounted on said seat and having, in part, a shape conforming to the shape of said bolster seat, and being provided with an opening for reception of said blade, a step bearing resting on the bottom of said blade-mounting housing in spaced relation to said bolster seat, for receiving a portion of said blade, said step bearing and the blade-mounting housing at the position where the step bearing is located having relative sizes providing play between the step bearing and housing allowing limited movement of the step bearing and blade relative to the housing, a loose connecting means connecting the bolster and step bearing to such extent that the step bearing resting on the bottom of the blade-mounting housing is entirely independent of said connecting means but providing means for withdrawing the step bearing from the housing.

3. A spindle according to claim 2 and in which the loose connecting means between the bolster and step bearing comprises a thin-walled flexible tube having a loose snap connection with the step bearing.

4. In a spindle, a blade, a blade-mounting housing having a substantially semi-spherical bolster seat, a bolster mounted on said seat and having, in part, a shape conforming to the shape of said bolster seat, and being provided with an opening for reception of said blade, a step bearing resting on the bottom of said blade-mounting housing in spaced relation to said bolster seat, for receiving a portion of said blade, said step bearing and the blade-mounting housing at the position where the step bearing is located having relative sizes providing play between the step bearing and blade relative to the housing, a tube loosely connecting the bolster and step bearing but providing means for withdrawing the step bearing from the housing, means for positively securing said tube against longitudinal movement in a position providing play for entirely independent relative movement between said step bearing and tube, and play for relative movement between said bolster and tube, said bolster being provided with a downwardly depending neck having an upwardly facing abutment spaced from the bolster proper, said tube overlapping the bolster neck and having a downwardly facing abutment, and spring means provided between said abutments for drawing the neck and bolster downwardly to retain the bolster properly seated on the bolster seat.

5. A spindle according to claim 4 and in which means is provided for positively securing the flexible tube against longitudinal movement.

6. In a spindle, a blade, a blade-mounting

housing having a substantially semi-spherical bolster seat, a bolster mounted on said seat and having, in part, a shape conforming to the shape of said bolster seat, and being provided with an opening for reception of said blade, a step bearing resting on the bottom of said blade-mounting housing in spaced relation to said bolster seat, for receiving a portion of said blade, said step bearing and the blade-mounting housing at the position where the step bearing is located having relative sizes providing play between the step bearing and housing allowing limited movement of the step bearing and blade relative to the housing, and means loosely connecting said bolster and step bearing for withdrawing the step bearing from the housing while allowing rela-

tive pivotal movement of the bolster and relative lateral movement of the step bearing.
